CHARLES F. GREGG, OF INDIANAPOLIS, INDIANA

CLEANING MACHINE.

Application filed October 28, 1925. Serial No. 65,314.

My invention relates to improvements in machines for dry cleaning delicate fabrics.

I have found that in the ordinary process of dry cleaning clothing and the like where fabrics of delicate texture are placed in the ordinary commercial cleaning machine and tumbled through the dry cleaning fluid the agitation to which these fabrics are subjected causes the threads to break or causes excessive wear thereon.

It is one of the objects of my invention to provide a cleaning apparatus in which, while the fabrics to be cleaned are held against tumbling and agitation and rubbing against one another and the sides of the machine, the cleaning fluid will be forced through the fabrics to be cleaned, loosening and removing all dirt therein without injury to the fabric.

For the purpose of disclosing my invention I have illustrated one embodiment thereof in the accompanying drawings in which

Fig. 1 is a perspective view of a machine embodying my invention;

Fig. 2 is a plan view partly in section;

Fig. 3 is an elevation partly in section showing more particularly the construction of the cleaning fluid container;

Fig. 4 is a bottom plan view of the restraining plate for the goods container, and

Fig. 5 is a sectional view of the goods container.

In the embodiment illustrated I provide a tank or receptacle 1 which is adapted to contain the cleaning fluid and which is preferably cylindrical in shape having a rounded bottom 2. The upper end of this tank is closed by a hood 3 having a door 4 hinged at its upper end 5 and inclined outwardly and downwardly and thereby held closed by gravity.

The tank is supported above the floor upon two pairs of legs 6 connected together by an arcuate cross bar 6^a and bolted or otherwise secured to the bottom of the tank. Due to the fact that the tank is circular and to the particular construction of the supporting legs the same sized legs may be used for various sized tanks.

Operating within the tank 1 is a container 7 substantially cylindrical in shape and having a foraminous bottom 8 which is spaced some distance above the lower edge 9 of the cylindrical container. This container is slightly smaller than the tank 1 and is provided on its outer surface near the lower edge with an annular flange 10 which helps

close the space between the container and the walls of the tank. The inner walls of the container near the foraminous bottom 8 are provided with inwardly projecting cup shaped fins 11. The goods are clamped in the container between the foraminous bottom and a foraminous clamp 12 adapted to fit within the container and provided at diametrically opposite points with sliding bolts 13 adapted to take into restraining openings 14 in the side walls of the container to thereby lock the clamping plate in adjusted positions in the container. The bolts are retracted and projected by means of an oscillating plate 15 mounted at the center of the clamping member and connected by links 16 with the different bolts. The bolts are practically mounted on a series of radial arms 17 secured at their outer ends to the rim 18 to which the foraminous material from which the clamping member is constructed is secured and on the under face of these arms and accordingly on the under face of the clamping member I provide a series of cup-like agitators 19.

The container is vertically reciprocated within the tank and to this end is provided on each side with vertical straps 20 the upper ends of which are connected through suitable slots 21 in the hood with the tops of reciprocating rods 22 mounted on the exterior of the tank. These rods are guided in suitable guide members 23 secured on the sides of the tank and are reciprocated by means of pitman rods 24 connected with counter-balanced crank arms 25 mounted on the driving shaft 26. The upper ends of the rods 22 are connected to sprocket chains 27 which pass over sprocket wheels 28 on a shaft mounted at the top of the hood and the opposite ends of these sprocket chains are connected to counter-balance weights 29 so that the weight of the container may be so counter-balanced that a minimum of power is required for reciprocating the same.

In operation the fabrics to be cleaned are placed within the container and the clamping member 12 is clamped and locked in position upon the top of the same holding the fabrics securely clamped between the clamping member and the bottom of the container. The container is then vertically reciprocated in the cleaning fluid contained in the tank and due to the extension of the cylindrical walls of the container beyond the foraminous bottom 8 and the annular fin 10 a large proportion of

the fluid is forced up through the fabric as the container descends. On the reverse movement the cleaning fluid passes down through the fabrics and as the container is elevated to 5 a point above the normal level of the liquid contained in the tank 1 the cups 19 and 11 act somewhat as suction members and agitators to increase the pumping action of the liquid as it passes downwardly through the fabrics 10 so that during the reciprocation of the container cleaning fluid is alternately forced upwardly and downwardly through the fabrics thoroughly cleansing the same and at the same time the fabrics themselves are held against 15 tumbling and rubbing action either against one another or against the sides of the container.

I have found in actual practice that the most delicate fabrics, such as Georgette crepe, chiffon and the like may be thoroughly cleaned 20 without the slightest damage.

The hood 3 prevents the fumes of the cleaning fluid from escaping into the operating room and also prevents the splashing liquid 25 from escaping. Due to the fact that the door 4 is hinged at its top and inclines outwardly and downwardly the door is maintained closed only by gravity and therefore in event of an 30 explosion of the gases of the fluid within the container will fly open under the force of the explosion so that no damage will be done to the apparatus. In order to insure the immediate closing of the door again I provide spring 35 stops 30 against which the door strikes, so that in event of an explosion taking place, which is liable to be followed by fire, the door will immediately fly closed and shut off the escape of flames into the operating room. .

I claim as my invention:

40 1. In a dry cleaning machine the combination with a cleaning fluid tank, of a container for the goods to be cleaned having a foraminous bottom, a foraminous adjustable clamping member adjustable in said container relatively to the bottom and constructed to clamp 45 the goods in said container between the clamping member and the bottom irrespective of the quantity of goods placed in the container and means for reciprocating said container 50 with the clamped goods into and out of the liquid contained in said tank.

2. In a dry cleaning machine the combination with a tank adapted to contain the cleaning liquid, of a tubular receiver for the goods

to be cleaned, means adjustable in said container for clamping the goods in said receiver against movement therein irrespective of the quantity of goods placed in said container and means for axially reciprocating said receiver into and out of the liquid contained in said 60 tank while the goods are held against movement in the container.

3. In a dry cleaning machine the combination with a tank adapted to contain the cleaning liquid, of a tubular receiver for the goods to be cleaned, foraminous means adjustable in said container for clamping the goods in said container against movement therein irrespective of the quantity of goods placed in the container and means for reciprocating the 70 container with the goods clamped therein into and out of the liquid in said tank.

4. In a dry cleaning machine the combination with a tank adapted to contain the cleaning fluid, of a tubular receiver for the goods, means adjustable in said receiver for clamping the goods in said receiver intermediate of its ends irrespective of the quantity of goods placed in said receiver and means for axially reciprocating said tubular receiver into and 80 out of the liquid contained in said tank.

5. In a dry cleaning machine the combination with a tank adapted to contain the cleaning fluid, of a receiver for the goods to be cleaned comprising a tubular shell, foraminous members in said shell intermediate of the ends thereof one of which is adjustable in said shell and relatively to the other for clamping the goods against movement in said shell irrespective of the quantity of goods placed therein and means for reciprocating said shell into 90 and out of the cleaning fluid in said tank.

6. In a dry cleaning machine the combination with a tank adapted to contain the cleaning fluid, of a receiver for the goods comprising a tubular shell, a foraminous bottom for said shell mounted therein at a point above the bottom edge of said shell, a foraminous adjustable clamping member adjustable in said shell relatively to the bottom and clamping the goods between it and said foraminous bottom irrespective of the quantity of goods placed therein to hold the goods against movement in the shell and means for axially reciprocating the shell into and out of the cleaning 100 fluid in said tank.

CHARLES F. GREGG.
